UNITED STATES PATENT OFFICE.

GUS W. SWANSON, OF MORGANTOWN, WEST VIRGINIA, ASSIGNOR TO THE UNITED STATES WINDOW GLASS COMPANY, OF MORGANTOWN, WEST VIRGINIA, A CORPORATION OF WEST VIRGINIA.

CAPPING-OFF DEVICE.

Application filed October 18, 1922. Serial No. 595,293.

To all whom it may concern:

Be it known that I, Gus W. Swanson, a citizen of the United States, residing at Morgantown, in the county of Monongalia 5 and State of West Virginia, have invented a new and useful Capping-Off Device, of which the following is a specification.

This invention is a device for capping-off glass cylinders, and for cutting such cylinders into flattening lengths incidental to the manufacture of window glass.

One of the objects of the invention is to produce simple means whereby an electric heating wire may be utilized for applying 15 the cracking tension to the glass. A further object is to provide a device of the character mentioned, which may be adjusted to cylinders of different diameters. A further object is to provide means whereby the heating wire may be snugly drawn around the cylinder to be operated on, and held in position to secure the cracking tension, its ends being so positioned as to insure a small gap 20 which will prevent short circuiting of the wire. A further object is to provide a device in which the horse normally employed to support the cylinder during the "capping-off" and "cracking off" operations, may be utilized to support the line wires and contacts complementary to the contacts of the 25 heating wire.

The invention will be hereinafter fully set forth and particularly pointed out in the claims.

35 In the accompanying drawing:—

Figure 1 is a top plan view of a horse with a capping-off device constructed in accordance with the invention applied thereto. Figure 2 is an end view thereof. Figures 40 3 and 4 are detail cross sectional views illustrating arrangements of line wire and contacts. Figure 5 is a longitudinal sectional view illustrating the capping-off device.

Referring to the drawings, a standard 45 type cylinder-supporting horse is shown, comprising two longitudinal bars 10 and 11, engaged and supported by a plurality of standards 12. Supported by the bar 10 are a plurality of divergent arms 13, provided 50 with telescoping rods 14, which engage cylinder-supporting arms 15, the inner ends of which are engaged by the longitudinally disposed anchoring bar 11. The last mentioned bar is T-shape in cross section, and

is connected to the bar 10 by uprights 16. 55 The construction thus far described is a well-known type of horse, commonly employed in window glass factories for supporting glass cylinders during the capping-off and cutting operations, and is disclosed 60 herein solely for illustrative purposes.

Secured to the bar 11 are a plurality of laterally extended brackets 17, which support longitudinally disposed conduit bars 18, provided with longitudinally disposed 65 open grooves 19 and 20, in which are located line wires 21 and 22 respectively, which may be connected in any desired manner (not shown), with suitable source of electrical energy. Secured to the top of each bar 18 are a plurality of contact plates 23, said plates being separated by spaces conforming 70 approximately to the normal flattening lengths into which a cylinder is usually cut. Said plates are electrically connected in suitable manner with the line wire 19, and are provided with a plurality of upstanding contact pins 24. Extending across each contact plate 23 and insulated therefrom is a contact socket 25, which is electrically connected 75 in suitable manner with the wire 20. The arrangement of the contact plates 23 and the sockets 25 is such that a circuit wire having one end connected to any one of the pins 24 and the other end connected with the socket 25 will place the wires 21 and 22 in circuit. 80

The capping-off device per se, comprises a switch 30, mounted upon an insulating base 31, said base being provided with a socket 32, into which is inserted one end of a contact member 33, which is secured in position by means of the binding screw 34, whereby 85 said contact member 33 is connected with one terminal of the switch 30. Said contact member is also enclosed within an insulating sleeve 34', which is somewhat shorter than the contact member so as to allow a small portion of the latter to project. To the projecting end of the contact member 90 33 is connected one end of the heating wire 34", the other end of said wire being connected with one end of a contact member 35, enclosed within an insulating sleeve 36. The other end of said contact member 35 projects beyond the sleeve 36 and is bent to 95 form an eye 37. The other terminal of switch 30 is connected by a flexible wire 38,

with another contact member 39, extending through an insulating sleeve 40, one end of said contact member projecting beyond the sleeve and being split as indicated at 41.

5 In practice, the cylinder is first taken down and placed upon the arms 15 of the horse in a manner well-understood in the art. When it is desired to cut the cylinder into lengths, the operator holds the switch member 31 and its attached insulating member 34' in one hand, and with the other drops the insulating sleeve 36 and its enclosed contact member 35 back of the cylinder. He then reaches under the latter and grasps the 10 sleeve 36, pulling it forward and up over the glass, finally hooking the eye 37 over any one of the pins 24. He then pulls upon the switch member 31 drawing the wire 34' tightly around the cylinder, after which the 15 split end 41 of the contact 39 is inserted into the socket 25, the crossing portions of the wire 34' lying close together but not in contact. He is then ready to turn on the current by means of the switch 30, and the capping and cracking off operations are carried 20 out in a manner well-known to those skilled in the art.

The advantages of the invention will be 25 readily apparent to those skilled in the art to which it appertains. It will be particularly noted that an electrically heated wire is conveniently used for the "capping-off" and "cracking-off" operations, and that the parts are so arranged that the wire 34' 30 may be readily drawn around cylinders of different sizes. A further advantage lies in the fact that the ends of the wire 34' may be brought close together so as to insure a very small gap, which will prevent short circuiting of the wire, and at the same time insure a substantially even cut around the cylinder along the line of cracking tension. By placing the line wires and contacts upon the horse which supports the cylinder, a 35 very convenient arrangement is provided by which the various operations are greatly facilitated.

Having thus explained the nature of the 40 invention and described an operative manner of constructing and using the same, although without attempting to set forth all of the forms in which it may be made, or all of the forms of its use, what is claimed is:—

55 1. A capping-off device of the character described comprising a portable switch member, a contact member in circuit with said switch member, a heating wire connected at one end to said switch member, and a second contact member connected to the other 60 end of said heating wire, each of said contact members having means for removably engaging a source of electrical energy.

65 2. A capping-off device of the character described comprising a portable insulating device provided with a switch, a contact rod

connected in normally fixed relation with one terminal of said switch, a heating wire connected at one end to said contact rod, a line contact member connected to the other end of said wire, and a line contact member connected with the other terminal of said switch, each of said contact members having means for removably engaging a source of electrical energy. 70

3. A capping-off device of the character described comprising a portable switch member, a line contact member in circuit with said switch member, an insulating tube enclosing said contact member, a heating wire connected at one end to said switch member, and a second line contact member connected to the other end of said wire, each of said contact members having means for removably engaging a source of electrical energy. 75

4. A capping-off device of the character described comprising a switch member, a line contact member in circuit with said switch member, an insulating tube enclosing said contact member, a heating wire connected at one end to said switch member, and a second line contact member connected to the other end of said wire, the last-mentioned contact member having one end shaped to 80 provide an eye. 90

5. A capping-off switch of the character described comprising a portable switch member, an insulating tube, a line contact rod passed through said tube, a flexible wire connecting said contact member with said switch member, a heating wire connected with said switch member, and an additional line contact member connected to the other end of said heating wire, each of said contact members having means for removably 100 engaging a source of electrical energy. 105

6. A capping-off switch of the character described comprising a portable switch member, an insulating tube, a line contact member secured within said tube, a flexible wire connecting said contact member with said switch member, a heating wire connected at one end to said switch member, a second line contact member connected to the other end of said heating wire, and an insulating tube enclosing the last mentioned contact member, each of said contact members having means for removably engaging a source of electrical energy. 110

7. A capping-off switch of the character 120 described comprising an insulating base, a switch thereon, a contact rod having one end inserted into said base and placed in circuit with one terminal of said switch, an insulating sleeve enclosing said rod, a heating wire connected at one end to the other end of said rod, a line contact member connected to the other end of said wire, an insulating sleeve enclosing the last-mentioned contact member, a second line contact mem- 125 130

ber, an insulating sleeve enclosing the same, and a flexible wire connecting the other end of said switch with the last mentioned contact member.

5 8. The combination with a cylinder-supporting horse, and line wires supported thereby provided with contacts, of a switch member, a heating wire connected with said switch member, and contacts connected respectively with the switch member and said heating wire, said last mentioned contacts having means for removably engaging contacts of said line wires.

9. The combination with a cylinder-supporting horse, line wires supported thereby, and a plurality of spaced apart sets of contacts associated with said line wires, of a switch member, a heating wire connected at one end to said switch member, and contacts connected respectively with the other end of said heating wire and with said switch member, and complementary to the first mentioned contacts.

10. The combination with a cylinder-supporting horse, line wires supported thereby, a contact plate connected with one wire and provided with a plurality of pin contacts, a contact socket connected with the other line wire and positioned contiguous to said contact plate, of a switch member, a heating wire connected at one end to said switch member, and contacts connected respectively to said switch member and the other end of said heating wire, and complementary to the first mentioned contacts.

11. The combination with a cylinder-supporting horse, of a bracket supported thereby, a conduit bar supported by said bracket, line wires sustained by said conduit bar, a plurality of sets of contacts secured to said bar and connected with the respective line wires, each set consisting of a single

socket contact and a plurality of pin contacts, of a switch member, a heating wire connected at one end to said switch member, and contacts connected respectively with said switch member and said heating wire, and complementary to the first mentioned contacts.

12. The combination with a cylinder-supporting horse, line wires supported thereby, a contact plate connected with one wire and provided with a plurality of pin contacts, a contact socket connected with the other line wire and positioned contiguous to said contact plate, of a switch member, a heating wire connected at one end to said switch member, a contact secured to the other end of said heating wire and having an opening complementary to said pin contacts, and a contact connected with the switch member and complementary to said socket.

13. The combination with a cylinder-supporting horse, and line wires supported thereby provided with contacts, of a heating wire provided with terminal means for removably engaging said contacts, and a switch controlling passage of current through the wire while engaged with said contacts.

14. The combination with a cylinder-supporting horse, and line wires supported thereby provided with contacts, of a heating wire provided with terminal means for removably engaging said contacts, means whereby any slack in said heating wire may be taken up while the wire is engaged with said contacts and extended around a glass cylinder, and a switch controlling passage of current through said wire.

In testimony whereof I have hereunto set my hand.

GUS W. SWANSON.
